OZONE-LAMP FIXTURE

Raymond B. Roney, Arcadia, Calif.

Application October 10, 1950, Serial No. 12,510

Term of patent 7 years

(Cl. D48—20)

To all whom it may concern:

Be it known that I, Raymond B. Roney, a citizen of the United States, residing at Arcadia, in the county of Los Angeles and State of California, have invented a new, original, and ornamental Design for an Ozone-Lamp Fixture, of which the following is a specification, reference being had to the accompanying drawing, forming part hereof, and wherein:

Figures 1 and 2 are, respectively, a front perspective view and a side elevation of an ozone-lamp fixture showing my new design.

The back of the fixture is flat.

I claim:

The ornamental design for an ozone-lamp fixture, substantially as shown and described.

RAYMOND B. RONEY.
